UNITED STATES PATENT OFFICE.

PETER ERICKSON, OF CHICAGO, ILLINOIS.

CUTTER-GUARD.

1,074,614.

Specification of Letters Patent.

Patented Oct. 7, 1913.

Application filed October 7, 1912. Serial No. 724,320.

To all whom it may concern:

Be it known that I, PETER ERICKSON, a citizen of the United States, residing at Chicago, in the county of Cook and State of Illinois, have invented certain new and useful Improvements in Cutter-Guards, of which the following is a specification.

This invention relates to guards for shapers and other wood-working machines for preventing injury to the operator from contact with the cutter.

The object of the invention is to provide a guard of the kind stated which can be easily attached to the machine without altering the structure thereof, and which can be readily placed in operative position, and swung out of the way when not in use. The guard is also so constructed that it holds the work firmly against the table. These objects are attained by a novel combination and arrangement of parts to be hereinafter described and claimed, reference being had to the accompanying drawings, in which—

Figure 1 is an elevation of the guard, partly broken away, in operative position. Fig. 2 is a plan view of the guard. Fig. 3 is a longitudinal section on the line 3—3 of Fig. 2. Fig. 4 is a cross section on the line 4—4 of Fig. 2. Fig. 5 is a horizontal section on the line 5—5 of Fig. 1. Fig. 6 is a bottom plan view of the supporting bracket of the guard. Fig. 7 is a perspective view of the cam to be hereinafter described.

In the drawings, 10 denotes the work table of a shaper or other wood-working machine having a vertical cutter-head 11 armed with knives 12 which operate above the table in the ordinary manner. The guard for protecting the operator's hands from being injured by the knives comprises a plate 13 which surrounds the cutter-head, said plate having a central opening 14 in which the cutter-head works. The operator's hands therefore cannot accidentally come in contact with the knives, and proper protection is afforded. The guard also serves to hold the work firmly on the table 10, and it is carried by the outer end of a horizontally extending arm 15 located above the table 10, and supported in a manner to be presently described. A bolt 16 and a wing-nut 17 adjustably secure the guard to the supporting arm thereof.

To the under side of the table 10, near one edge thereof, is bolted or otherwise rigidly secured a bracket 18 having at one end a

depending portion 19 to which is pivoted a socket member 20 which latter supports a standard 21. The socket-member has two lugs or ears 22 between which the part 19 extends, and in the opposite side edges of the latter are apertures in which seat pivot screws 23 carried by the lugs, whereby the pivotal connection between the part 19 and the socket-member is had.

The standard 21 is angular in cross-section, except its lower portion which passes into the socket of the member 20, and it is held in place therein by side and bottom screws 24. The socket-member is located slightly beyond the edge of the table 10 so that the standard may clear the same, and the latter rises a suitable distance above the level of the table.

Above the table 10, the standard 21 carries a clamping member 25 for holding the standard in upright position. This member is held in place on the standard by a set screw 26. The member 25 is so located that the table is between the same and the bracket 18, in which latter is an aperture which registers with an aperture in the table. Through these apertures and an arcuate slot 27 in the member 25 passes a bolt 28 one end of which projects from the bottom of the bracket and has in said projecting end a transverse slot to receive a wedge-shaped key 29. The other end of the bolt rises above the member 25, and said end is threaded to receive a nut 30 which screws down on said member. The upper end of the bolt is provided with a suitable handle bar 30^a which passes through a transverse aperture therein.

On the standard 21, above the member 25, is adjustably mounted a support for the arm 15, said support comprising a top 31, and a bottom 32 connected at each end by laterally spaced webs 33 between which latter and between the top and bottom, the inner end of the arm extends, said end of the arm being slotted lengthwise, as indicated at 34 so that it may straddle the standard. Beneath the top 31, the top of the arm is engaged by a clamping plate 35 which latter has on its under side a boss 36 which fits in the slot 34, and has a threaded aperture to receive a bolt 37 passing upward through an aperture in the bottom 32 and through the slot 34. Around the bolt, between the boss 36 and the bottom 32, is coiled a spring 38. The head 39 of the bolt engages the under side of the

bottom 32 and carries a transverse handle bar 40. Upon tightening up the bolt, the arm 15 is clamped between the plate 35 and the bottom 32. The spring 38 serves to hold 5 up the plate 35 when the arm 15 is removed for the purpose of changing the same.

From the top 31 rises a boss 41 having a vertical aperture to receive the standard 21 and in the bottom 32, in line with said aperture, is an aperture through which the standard also passes. The aperture in the boss 41 is large enough to accommodate a longitudinal key 42 which is loose and is adapted to be jammed against one side of 10 the standard by means of a cam 43 mounted in a transverse opening in the boss 41, said opening intersecting the aperture. One end of the cam has a lever-arm 44, whereby 15 the cam may be rocked. The cam is in contact with the key and when it is rocked in 20 one direction, the key is jammed tightly against the standard 21, whereby the supporting member of the arm 15 is rigidly held in place on the standard. Upon rocking 25 the cam in the opposite direction, the supporting member is released, and it can then be shifted up or down on the standard to locate the arm 15 and the guard 13 the 30 desired distance above the table 10. The cam 43 is operated by a rod 45 connected to the lever-arm 44 and supported at its free end by a fork 46 mounted on the top 31. A grip 47 is screwed on the rod 45 against 35 the fork, so that by turning said grip, the rod is drawn forward or backed to operate the cam. The fork and grip serve to lock the cam in clamping position.

To the upper end of the standard 21, in axial alignment therewith, is secured a rod 48 on which is slidably mounted a sleeve 49. The upper end of the sleeve 49 carries a projecting pin or abutment 50 and from the bottom of the sleeve extends a pin 51 which seats in an aperture in the top of the standard 21, said pin 51 serving to hold the sleeve against rotation on the rod 48. Above the sleeve 49, the rod 48 carries a bracket 52 supporting a pulley 53. On the top 31 of the supporting member of the arm 15 are 45 ears 54 which support a pulley 55. A hoisting line 56 is connected at one end to the boss 41 from which it passes upward to the pulley 53, and over the same, and thence downward and over the pulley 55. The line 50 56 is provided for raising or lowering the supporting member of the arm 15 on the standard 21. When said member passes onto the sleeve 49 and reaches the abutment 50, a continued pull on the line 56 causes the 55 sleeve to slide up on the rod 48, and when the locking pin 51 is entirely withdrawn from the aperture in the standard 21, the sleeve is released and may be rotated on the rod 48, so that the guard 13 and its arm 15 60 may be now swung sidewise, entirely clear

of the table 10. The guard may also be swung down alongside the table 10 to leave the latter entirely clear, by removing the bolt 28. This releases the clamping member 25 and enables the standard 21, and all 70 the parts carried thereby to be swung down, the pivots 23 permitting this. The apertures in the bracket 18 and the table 10 through which the bolt 28 passes, have diametrically opposite key-ways 57 to accommodate the key 29. A quarter turn of the bolt 28 brings the key in line with the key-ways, after which the bolt may be removed. The arcuate slot 27 enables the standard 21 to be rotated to turn the guard 80 in any direction across the table 10, within the limits of the slot, after loosening the side screw 24, so that the guard may be properly positioned relative to the cutter-head 11.

It will be evident from the foregoing that the guard has a wide range of adjustment, and it can also be quickly swung clear of the table or replaced in operative position.

The manner of attachment is such that 90 the guard can be readily applied to the machine without any alteration or change in the structure of the latter.

The preferred embodiment of the invention has been shown, but it is to be understood that various changes in the structural details may be made without a departure 95 from the spirit and scope of the invention.

I claim:

1. The combination with a work-table and 100 a cutter; of a support mounted adjacent to the edge of the table, a member pivoted to said support, a standard carried by said member and rotatable therein, means for holding the standard against rotation, a cutter-guard, a support for the cutter-guard mounted on the standard, a slotted member carried by the standard, and a clamping bolt passing through the table and the slot of 105 said member.

2. The combination with a work-table and 110 a cutter; of a support mounted adjacent to the edge of the table, a member pivoted to said support, a standard carried by said member and rotatable therein, means for holding the standard against rotation, a cutter-guard, a support for the cutter-guard mounted on the standard, and means for 115 locking the standard in upright position, said means having an adjustable fastening 120 to permit rotation of the standard.

3. The combination with a work-table and 125 a cutter; of a support mounted adjacent to the edge of the table, a member pivoted to said support, a standard carried by said member and rotatable therein, means for holding the standard against rotation, a cutter-guard, a support for the cutter-guard mounted on the standard, a plate carried by 130 the standard and having an arcuate slot,

and a fastening means passing through the slot and the work-table.

4. The combination of a standard, a cutter-guard, a support for said guard slidably and non-rotatably mounted on the standard, and a rotatable member carried by the standard onto which member the aforesaid support is movable.

5. The combination of a standard, a cutter-guard, a support for said guard slidably and non-rotatably mounted in the standard, a rotatable and slidable member carried by the standard onto which member the aforesaid support is movable, means for locking the member, and an abutment on the member engageable by the support for sliding said member to release the same.

6. The combination of a standard, a cutter-guard, a support for said guard slidably and non-rotatably mounted on the standard, a rod rising from the standard, a sleeve slidable and rotatable on the rod onto which sleeve the support is movable, and an abutment and a pin on the sleeve, said pin entering an aperture in the standard for locking the sleeve against rotation, and the abutment being engageable by the support to slide the sleeve and disengage the pin to release the sleeve.

7. The combination of a standard, a cutter-guard, a support for said guard having an aperture through which the standard passes and said support having a transverse opening intersecting the aperture, a key loose in the aperture, a cam mounted in the opening and engageable with the key for

jamming the same against the standard, an arm extending from the cam, a fork mounted on the support, a rod connected to the arm and supported by the fork, and a member screwed on the rod against the fork.

8. The combination of a support having spaced top and bottom portions, an arm having a slotted portion located between the top and bottom portions of the support, a cutter-guard carried by the arm, a plate mounted on the slotted portion of the arm, a bolt passing through the slot of the arm and the bottom portion of the support, and engageable with the plate, and a standard on which the support is mounted, said standard passing through the slot of the arm.

9. The combination of a support having spaced top and bottom portions, an arm having a slotted portion located between the top and bottom portions of the support, a cutter-guard carried by the arm, a plate mounted on the slotted portion of the arm, a bolt passing through the slot of the arm and the bottom portion of the support and engageable with the plate, a spring coiled around the bolt between the plate and the bottom portion of the support, and a standard on which the support is mounted, said standard passing through the slot of the arm.

In testimony whereof I affix my signature in presence of two witnesses.

PETER ERICKSON.
